Revo, Inc., Deerfield, Mich.

Application March 17, 1949, Serial No. 81,853

6 Claims. (Cl. 312—97.1)

1

This invention relates to vending machines, and it has particular reference to the provision of a vending machine from which bottled beverages or other articles may be successively dispensed in a chilled condition through the operation of coin controlled mechanism.

According to the present invention, there is provided an insulated cabinet structure in which is mounted a rotatable magazine adapted to contain a plurality of the articles to be dispensed. The magazine may be progressively rotated by means of an operating handle positioned on a cover or door for the cabinet, whenever a suitable coin is inserted in the machine, and as long as the magazine contains a bottle in a position to be dispensed. Provision is also made to store the articles in concentric rows, and to transfer the articles from one row to another as they reach a predetermined position in the cabinet, so that the magazine contents may be successively ejected through an access opening in the cover.

The machine also includes a refrigeration plant, so organized that it may be assembled with the cabinet as a complete unitary structure, thereby simplifying problems of manufacture and servicing. Other features of the invention, conducive to the production of an inexpensive, simple and durable vending machine, will be pointed out as this description proceeds.

The invention will be fully understood from the following explanation of a typical embodiment, illustrated in the accompanying drawings, wherein:

Fig. 1 is a front elevation of the vending machine;

Fig. 2 is a front elevation of the machine with the door removed, showing the bottle magazine;

Fig. 3 is a fragmentary transverse section on the line 3—3 of Fig. 2, with parts removed, showing how the bottles are ejected;

Fig. 4 is a fragmentary view of the upper portion of the casing, with the bottle magazine removed, showing the refrigeration evaporator casting in front elevation;

Fig. 5 is a longitudinal vertical section through the machine;

Fig. 6 is an enlarged fragmentary front elevation of the bottle magazine;

Fig. 7 is a perspective view of a magazine divider;

Fig. 8 is an elevation of the inner face of the door;

Fig. 9 is an elevation of the inner face of the door with the control mechanism compartment cover removed;

2

Fig. 10 is an enlarged fragmentary section on the line 10—10 of Fig. 2, showing a retainer latch;

Fig. 11 is an enlarged fragmentary elevation of a magazine escapement latch;

Fig. 12 is a section on the line 12—12 of Fig. 11;

Fig. 13 is an enlarged fragmentary section through the longitudinal axis of the door;

Fig. 14 is an elevation of the inner face of a coin operated gate;

Fig. 15 is an enlarged fragmentary elevation of the coin actuated mechanism as viewed from the inner face of the door; and,

Fig. 16 is a section on the line 16—16 of Fig. 13.

Referring primarily to Figs. 1 and 5, the machine includes a cabinet having a cylindrical outer wall 21 within which is positioned a shorter spaced inner wall 22 extending from the front of the cabinet to spaced inner and outer back walls 23 and 24. The structure is welded or otherwise connected to a supporting base 25, which is provided on its front end with lugs 26 for a hinge pin 27 to receive a pivotally mounted front door or cover 28. This door is also of double wall construction, and it may be retained in closed position by a hasp 29, pivotally mounted on the outer cylindrical wall 21 and adapted to latch over a catch plate 31 secured to the door rim. A barrel lock 32 is advantageously incorporated in the hasp, to prevent unauthorized entrance into the cabinet. Insulating material 33 is disposed between the spaced walls to reduce the transfer of heat therethrough.

The outer face of the door 28 is provided with devices by means of which a purchaser may obtain a bottle from the cabinet. These include a plate 34 formed with a coin slot 35, a coin return knob 36, and a signal light window 37 to indicate to the customer whether the machine is operating. There is also provided a second plate 38 having a coin return pocket 39 and a bottle cap remover 41. An operating handle 42, pivotally mounted at the center of the door, may be swung downward as indicated by the arrow. Bottles dispensed by the machine are ejected through a circular opening 43 at the bottom of the door 28, which is normally closed by a spring-biased hinged shutter 44.

From the customer's viewpoint, the operation consists in inserting a suitable coin in the slot 35, and, if it is not rejected, in then swinging the handle 42 through a limited arc. A bottle B will then be thrust forward through the opening 43 to swing the shutter 44 down, and expose the end of the bottle, which comes to rest against a ledge 45 on the inner surface of the shutter.

The customer may then remove the bottle and detach the cap by insertion into the opening 41. If the coin is not of the right denomination, or is spurious, or if the machine is not conditioned to dispense an article, the coin will be returned to the pocket 39, and the operating handle 42 cannot be rotated.

The bottles within the cabinet are supported in a magazine structure, which is shown in Figs. 2 and 5 to 7. This magazine comprises an inner cylinder 51 and an outer cylinder 52, between which extend a plurality of generally radial ribs or dividers 53. Each divider is formed at its ends with peripheral flanges 54 and 55, by means of which it may be welded or bolted to the cylinders 51 and 52. The portion 56 of the divider adjacent the inner flange 54 may extend the full depth of the magazine, but the outer portion 57 is cut away to provide a slot 58, and it is also inclined with respect to the portion 56 toward the direction of rotation. The portion 57 merges into the flange 55 through a reverse bend section 59, which also extends the depth of the magazine, and a terminal radial portion 61 which is formed with a forwardly projecting finger 62.

The inner and outer cylinders 51 and 52 are provided at their rear ends with annular flanges 63 and 64 to provide limit stops for the bottles. Advantageously, filler pieces 65 are also welded between the flange 63 and the radial portions 56 of the dividers to prevent longitudinal displacement of the bottles. The interconnected cylinders 51 and 52 are mounted for rotation on a centrally positioned forwardly extending axle 67, which passes through the back wall 23 and is anchored in a column 68 extending upwardly from the outer wall 21. The axle 67 provides a bearing for a hollow shaft 69 to which is secured a series of radial vanes 71 which extend and are connected to the inner cylinder 51. As is shown in Fig. 2, the sectors between the vanes may be utilized to store bottles for pre-cooling, although in the particular embodiment shown, such bottles are not subject to automatic dispensing while in this position. The forward end of the hollow shaft 69 is also pierced by a diametrically positioned driving rod 72, by means of which the magazine is coupled to the operating handle 42.

The magazine is partitioned into two concentric tiers by an annular spacer ring 74 provided with a flange 75 for connection to the back wall 23, and which projects into the slots 58. It will be seen that the parts are so dimensioned that the ring 74 forms pairs of bottle receiving cells between the cylinders 51 and 52 and adjacent dividers 53. A portion of the ring 74 is cut away on the advancing side of the magazine, and below but near the horizontal diameter, to provide a gateway or opening 76 sufficiently long to permit a bottle to roll gently through from the inner to the outer cell in the event the outer cell is unoccupied. A guide plate 77 is secured to the ring 74 at the back of the gateway 76, to retain the bottle from rearward linear movement during the interval required for the bottle to be stopped by the flange 64.

It will be seen that bottles may be stored in the cells to rest on the outer cylinder 52 and the ring 74 and against one or the other of adjacent dividers 53 when the bottles are in the lower half of the magazine, and against the inner cylinder 51, ring 74, and dividers in the upper half. The rotation being clockwise, as seen in Fig. 2, and the discharge opening 43 being disposed on the ver-

tical diameter, the lowermost bottle in the magazine is therefore the bottle which will be dispensed. The forcible ejection of this bottle is effected by a leaf spring 78, secured to the back wall 23 to enter the lower outer cell, as shown in Figs. 3 and 5.

As the magazine is advanced, the outer cells become progressively emptied, and eventually an empty outer cell passes the gateway 76, to cause the bottle in the inner cell of the pair to roll under gravitational force into the outer cell, as is shown in Figs. 2 and 6. If the outer cell is occupied, the lower edge of the gateway acts as a cam to return the bottle to the inner cell and through the slight distance it moved to abut the outer bottle. When the outer cell is empty, the inclination of the portion 57 of the divider serves as track along which the bottle may roll gently to engage the edge of the portion 61. As the magazine continues to be advanced, the bottle may then roll over the edge of the portion 61, to assume positions as shown.

It is deemed beneficial to make the slots 58 as wide as is practical, both to reduce the weight of the magazine and to provide for free circulation of air. Air circulation is also enhanced by providing apertures 79 in the ring 74. Circulation is enforced around the magazine and its contents, to cool the bottles, by a refrigeration unit mounted on the back of the cabinet.

The refrigeration unit comprises a hermetic compressor 81 discharging compressed refrigerant into a condenser 82, which in turn supplies the fluid to an evaporator coil 83 contained in a housing 84. The discharge end of the evaporator is connected to the compressor in the usual known manner, and automatic off-and-on operation is obtained by means of a cold control switch 85, as is common practice with apparatus of this character. The evaporator housing 84, and the compressor and condenser, are all mounted on a plate 86 equipped with supporting brackets 87 and 88, which plate is bolted onto the outer back wall 24. The walls 23 and 24 are provided with aligned openings 89 through which a portion of the housing 84 projects, as is best shown in Figs. 4 and 5; and the outer cylindrical wall 21 is extended to form a protective casing for the unit.

The housing 84 is formed with an outer shell 91 larger than the openings 89 and with a spaced inner shell 92 of substantially the same size as the openings, and insulating material may be placed between these shells to prevent heat losses. The inner wall 92 supports a generally cylindrical baffle wall 93, formed with an impervious face 94 extending within the cabinet, and with an annular discharge passage 95 at its lower margin. An induction passage 96 is formed between the top of the baffle 93 and the inner housing wall 92. The housing contains a small motor 97 provided with a fan 98. Upon operation of the refrigeration compressor, the motor 97 is energized, to draw air in the cabinet through the housing 84, around the coil 83, for discharge through the orifice 95. The refrigerated air circulates around the magazine under high velocity, thereby cooling the bottles rapidly to the desired temperature.

The mechanism for rotating the bottle magazine is contained, to a large extent, in a pocket 101 formed in the door 28. To this end, the inner wall or liner 102 of the door is cut away to provide a rectangular opening which is framed with sheet metal walls 103 and a casing 104, as shown in Figs. 8 and 9. A reinforcing and supporting plate 105 is positioned on the bottom of the pocket adja-

cent the outer all 106 of the door, and the parts are interconnected by welding or screws, as may be desired. The plate 105 is drilled to provide an aperture, adapted to align with the axis of the magazine axle 67, in which is positioned a supporting bushing 107 providing a bearing for a shaft 108, whose outer end extends through the wall 106 for connection to the operating handle 42. As is best shown in Figs. 5 and 16, the inner end of the shaft 108 projects into the hollow magazine shaft 69 when the door is closed, thereby maintaining the shafts in alignment and providing mutual support.

A sleeve 109, shorter in length than the shaft 108, is positioned over the bushing 107, and it is connected for limited rotation with the shaft by a set screw 111 extending through a slot 112 formed in the bushing adjacent its inner end. The inner end of the sleeve 109 has welded thereto a circular plate 113 from which project three uniformly spaced studs 114 extending through arcuate slots 115 (Figs. 8 and 9) formed in an annular ratchet or overrunning clutch 116. The studs 114 are surrounded by coil springs 117 which provide resilient supports for the ratchet 116, and the parts are retained in assembled relation by any suitable means, such as cotter pins 118 passing through the ends of the studs. The ratchet 116 is formed with teeth 119 in its flanged portion, opposed pairs of which engage the driving rod 72 when the door 28 is closed.

The studs are normally retained at one end of their companion slots 115 by means of a pair of light tension springs 121 having one end connected to the ratchet, and the opposite end to posts 122 also fastened to the plate 113. Upon closing the door, the ratchet is free to move both axially and rotatively sufficiently to effect engagement of the teeth 119 with the rod 72, and thereby provide a driving connection between the handle 42 and the magazine. Upon movement of the handle, there is initially a limited amount of lost motion, during which interval the studs 114 move through the slots 115 until they engage the opposite ends thereof. The reason for providing such lost motion will be made apparent hereinafter. Continued movement of the handle 42 then causes the magazine to rotate through the engagement of the rod 72 with the driving flanks of the teeth 119 and until the set screw 111 engages the end of the bushing slot 112. When the handle is released for rotation in the opposite direction, the cam flanks of the teeth 119 ride over the rod 72 for engagement with the next pair.

As heretofore explained, the operation of the handle 42 is made dependent upon inserting a coin in the slot 35 of the plate 34. The coin passes through a chute 125 (Figs. 5 and 9) into a coin detector or "slug rejector" 126, where it is automatically tested, and from which it is returned to the receptacle 39 if it is not genuine or is of the wrong denomination. It is deemed unnecessary to describe the detector mechanism in detail, as it is of a known type. In brief, it includes devices for analyzing the coin with respect to size and composition, including a magnetic element 127 which must be energized to enable the detector to function. If current is not supplied, then good as well as spurious coins will be rejected. The return knob 36 may also be manually operated to cause a finger 128 to direct the coin into the return pocket 39.

The electrical characteristic of the detector 126 is herein utilized to decondition the vending machine in the event it is empty, or if there has been

a failure of power supply to the refrigerating unit which precludes cooling the bottles to a suitable temperature. The magnet 127 is connected in parallel with an indicator lamp 129, also mounted in the pocket 101 in line with the window 37, and current is supplied through a service cord 131 concealed in the door insulation, which extends to the rear of the cabinet for connection in parallel with the compressor service cord 132. The cord 131 is also connected through a normally open switch whose contact button 133 projects through the door liner 102 below the casing 104. The button 133 may be depressed to close the circuit by means of a leaf spring 135 mounted on the inner face of the door 28, and so located and bent as to be engageable by a bottle in the magazine cell which will next be brought into dispensing position. If there is no bottle in such cell—designated as 136 in Fig. 2—the spring 135 will move inwardly, thereby releasing the button 133 to open the circuit and thus decondition the machine. When the spring 135 is depressed by contact with a bottle in cell 136, the control switch is closed, thus enabling the machine to undergo its dispensing operation.

The coin released mechanism for preventing operative rotation of the handle 42 includes a cam sector 141 mounted on the sleeve 109, and formed on its upper portion with an arcuate slot 142 and an outwardly projecting finger 143. A gate 144, provided with hinge pin lugs 145, is pivotally mounted on a pin 146 by means of lugs 147 struck out from the plate 105, and the gate is normally urged against the sector 141 by a hinge pin spring 148. The finger 143 then projects beyond the edge of the gate 144, which accordingly provides a latch to restrain the movement of the handle and associated parts. The gate 144 is also formed with an arcuate ledge 149, which projects into the slot 142, and with a raised curved guide 151 having a tapered nose 152 at its outer end. The margin of the gate above the ledge 149 is formed with a recessed flange 153 adapted to underlie the coin detector 126.

When a suitable coin C is inserted in the machine, and is accepted by the detector 126, it will be diverted into a channel for delivery to the recessed portion 153 of the gate 144, and thus come to rest on the ledge 149, as shown in Fig. 15. In this position, the coin overlaps the vertical edge of the gate, and it will be contacted by the finger 143 upon initial movement of the sector 141. The movement imparted to the coin causes it to abut the tapered nose 152, thereby swinging the gate outwardly, and enabling the coin to slide or roll over the raised guide 151. This motion permits the finger 143 to pass in back of the gate, and thereby release the handle 42 for continued rotation. When the coin reaches the end of the ledge 149, it falls to the bottom of the pocket 101.

Other latching mechanisms are provided to maintain the bottle magazine in correct or indexed position, and to release it for movement by the ratchet 116. It will be readily understood that the weight of the magazine is apt to be unbalanced, due to the distribution of bottles therein, and accordingly it would, unless restrained, tend to rotate under gravitational influence and come to rest in random position. A holding or service latch, Figs. 2 and 10, is provided to restrain the magazine when the door 28 is open. This latch comprises a plate 155 mounted on the face of the cabinet by means of screws, and carrying a pin 156 on which is pivot-

ally mounted a detent 157, normally urged inwardly toward the magazine by a hinge spring 158. The inner end of the detent is slotted to engage any one of the fingers 62, and thus hold the magazine in any of the positions in which an outer bottle cell is aligned with the opening 43. When the door 28 is closed, the detent 157 is retracted from the finger, as shown in solid lines in Fig. 10.

A running position magazine latch 161 is carried by the door 28, being mounted on the inner liner 102 adjacent the horizontal diameter. It is adapted to interlock with a divider 53 as the door is closed, and just before the detent 157 is disengaged. This latch, as shown in detail in Figs. 11 and 12, includes a pair of spaced angle brackets 162, between which extends a rivet 163 serving as a support for a rotatably mounted, generally semi-circular, latch element 164. The element 164 is formed with an offset shoulder 165 adjacent its outer end, and the shoulder is normally biased to engage a finger 62 by means of a spring 166, anchored between one bracket 162 and a pin 167 carried by the element 164 and projecting through a bracket slot 168.

The unbalanced weight of the magazine, or the movement imparted to it by the handle 42, is sufficient to force the shoulder 165 downward against the urge of the spring 166, and thus permit the magazine to rotate and force the element 164 from the full to dot-and-dash line position of Fig. 12. As soon as the previously engaged divider 53 clears the element 164, the spring restores it to its original position. The element 164 is normally held in a locked and immovable position by linkage interconnected with the coin cam sector 141.

Reverting to Figs. 13 and 15, it will be seen that the lower portion of the sector 141 is formed with an arcuate periphery 169 having a pin 169 located at its center, to engage a notch 171 formed in a draw bar 172. The bar is provided at its outer end with a channel shaped clip 173 which engages around the arcuate portion 169 to provide a guide and retainer. The bar 172 is also formed with an angularly inclined struck-out ear 174, which is adapted to be contacted by an offset portion 175 on the sector periphery, after the sector has been rotated a few degrees. The draw bar is normally retained in the position shown in Fig. 15 by a laterally disposed tension spring 176 anchored between pins 177 and 178 respectively disposed on the mounting plate 105 and the bar 172.

The inner end of the draw bar 172 is provided with a pivot bushing 179 for one end of a bent link 181 which extends laterally through a guide channel 182 to the latch 161. A guide bushing 183 is mounted on the inner bracket 162 to provide a slide bearing for the end of the link, which passes through the bushing and bracket to enter a circular aperture 184 formed in the latch element 164. When the end of the link is so positioned, the latch element is locked from rotation about its pivot 163, and accordingly the magazine cannot be advanced.

Upon initial movement of the sector 141, the pin 169 carries the draw bar 172 and link 181 to the right, as viewed in Fig. 15, thereby withdrawing the remote end of the link from the aperture 184 to permit rotation of the element 164 under the influence of the magazine. At the same time, the spring 176 holds the notch 171 in engagement with the pin 169, causing the draw bar to rotate upwardly about the pivot 179. The guided linear movement of the link 181 imparts

substantially linear motion to the pivot 179, thus causing the ear 174 and the offset sector portion 175 to approach each other rapidly. These actions take place concurrently with the lost motion of the ratchet plate studs in their slots 115.

As the ratchet teeth 119 begin to drive the magazine to depress the element 164, the offset portion 175 of the sector 141 contacts the ear 174 to rotate the draw bar 172 away from the sector and against the urge of the spring 176. The notch 171 is thereupon released from the pin 169, and the spring 176 retracts the draw bar 172 to its original position. The latch spring 166 has by this time returned the latch element 164 to its horizontal position, and accordingly the guided end of the link 181 may enter the aperture 184 to stop the magazine by engagement with the next divider finger 62.

The extent of rotation of the handle 42, which is determined by the length of the slot 112 in the bushing 197 and the engagement therein of the shaft pin 111, is made such as to provide for the movement of the link 181, plus the rotation of the magazine a sufficient distance to bring the charged cell 136 into alignment with the dispensing opening 43. Thereafter the handle 42 and connected members are restored to their initial position by a tension spring 186 connected between pins 187 and 188 secured to the sector 141 and mounting plate 105. When the sector is so restored, the pin 169 again drops into the draw bar notch 171 to reestablish its driving connection.

The return motion, which causes the cam flanks of the ratchet teeth 119 to ride over the drive rod 12, may be accompanied by a tendency to rotate the magazine in the reverse direction. Such tendency may also be present because of the distribution of the bottles. Accordingly, the latch 161 further includes a channel shaped member 191, mounted over the brackets 162 by means of a pin 192, and normally urged outwardly into binding engagement with the brackets 162 by a hinge spring 193. The member 191 may be readily depressed by the pressure of the dividers passing thereover, but as the divider engages the latch shoulder 165, the member 191 is released and it then projects over the divider. Reverse rotation of the magazine is accordingly forestalled, and the next operation of the handle 42 will bring the next cell into correct alignment.

As shown in Fig. 8, the pocket 101 is provided with a pair of cover plates 195 and 196 which are detachably connected to the casing 104. These may be faced with insulating material 197. The lower cover 196 also carries a pair of spaced pins 198, on which is slidably mounted a retainer 199, adapted to be moved laterally by reason of inclined slots 201 positioned over the pins. The portion of the pocket 101 below the plate 196 is occupied by a cash and cap box 202, which may be readily removed by sliding the retainer 199 upwardly, and grasping the box through finger holes 203. Coins falling from the ledge 149 pass into one side of the box 202. Bottle caps which are deposited in the door opening 41 are directed through a duct 204 into the other side of the box, from which they may be removed with the 70 coins when the machine is refilled.

It is believed that the operation of the machine has been so fully explained as the description has developed that only a brief summary is indicated. The machine is shown as having a magazine containing twenty-eight cells, arranged in

two concentric tiers, although it will be readily understood that a greater or less number may be employed, depending upon the size of the cabinet. The lowermost cell is empty, as the spring 78 ejects the bottle therefrom as fast as the cell comes into this position. The attendant will therefore normally charge the remaining cells with bottles, utilizing those which have been stored between the vanes 71 in the outer cells in the lower right quadrant, as viewed in Fig. 2. During the charging operation, the detent 157 holds the magazine in position, but the attendant may readily release it to effect rotation, if so desired.

Upon closing the door 28, the latch 161 engages the right hand horizontal divider while the detent 157 becomes disengaged, and the leaf spring 135 is pressed against the switch button 133 to energize the magnet 127 and condition the detector 126 for operation. As coins are inserted into and accepted by the machine, the handle 42 may be operated to dispense the bottles successively. When the initially empty cell reaches the gateway 76, the bottle in the companion inner cell is transferred, and this action is continued until the last bottle passes from cell position 136 to be dispensed. The release of the spring 135 thereupon deenergizes the detector, placing it in a condition to return all coins, and the current failure also extinguishes the signal lamp 129 to indicate to customers that the machine is empty.

If there should be a power failure which would stop the refrigerating apparatus, and thus permit the cabinet contents to warm up, the detector 126 is also deconditioned, as its circuit is taken through the compressor service cable.

It is to be noted that the present invention involves numerous improvements in vending machines of the magazine type. Servicing is effected simply by opening the door, which of course is accessibly positioned, and the coin control devices are carried in a concealed and protected pocket in the door. The indexing of the magazine is also positive, and is effected in running position by latch means which are interlocked with the coin release mechanism. The coin control itself is quite simple, involving relatively few parts, but acting positively both to lock and release the operating handle. It is to be noted that, when a coin has passed to the gate ledge 149, and motion of the handle is instituted, an accidental retrograde motion will not deprive the customer of his purchase. If the initial motion is limited, the coin is still retained on the ledge, while if it has been enough to clear the latch shoulder 165, the handle cannot be reversed enough to cause the finger 143 of the sector 141 to pass beyond the edge of the gate 144. This is because the lower face of the shoulder 165 provides a stop for the divider finger 62 which has just passed it.

While the invention has been described with respect to a single embodiment, it will be apparent that numerous modifications and variations may be effected without departure from its principles. It is accordingly intended that the invention should not be limited to the precise details shown, but that it should be regarded as encompassing all the combinations and parts which are within the scope of the following claims.

I claim:

1. A dispensing apparatus comprising a cabinet having an open end, a main door closing said end, a cylindrical magazine having its axis hori-

zontally mounted in the cabinet and extending toward the door, radially spaced dividers in the magazine to partition it into a plurality of circumferentially disposed article cells, an access opening in the main door adapted to be successively aligned with the cells as the magazine is rotated, latch means mounted on the door and adapted to engage the magazine and restrain it from rotation, said latch means engaging the magazine at successive positions of alignment between the access opening and cells, a drive shaft extending through the door, an overrunning clutch connection between the drive shaft and the magazine, coin controlled means for releasably holding the drive shaft from rotation, stop means for the drive shaft to limit its motion to an arc sufficient to rotate the magazine through an arc subtended by a magazine cell, and means operative upon release of the holding means for momentarily disengaging the latch as the drive shaft is rotated to permit rotation of the magazine the arcuate distance of one cell only.

2. A dispensing apparatus comprising a cabinet, a main door closing one end of the cabinet, a cylindrical magazine rotatably mounted in the cabinet and divided into a plurality of circumferentially disposed article cells, a drive shaft for the magazine extending through the door and operable from the exterior thereof to rotate the magazine, a detachable one way clutch connection between the drive shaft and the magazine, an access opening in the main door adapted to be aligned successively with said cells as the magazine is rotated in one direction through said shaft and clutch connection, a latch adapted to engage the magazine and restrain it from rotation in said one direction, stop means for limiting the arc through which the drive shaft may be rotated, coin controlled means for releasably holding the drive shaft from rotation in said one direction, a lock member for the latch, a linkage between the drive shaft and the lock to release the latch upon initial movement of the drive shaft in said one direction after the drive shaft holding means has been released, said shaft stop means being such as to limit shaft movement to an arc bringing said cells successively in line with the access opening, and means included in said linkage to recondition the latch lock before the drive shaft rotates in said one direction to its limit.

3. A dispensing apparatus comprising a cabinet having an open end, a main door closing said end, a cylindrical magazine rotatably mounted in the cabinet and having its axis of rotation disposed horizontally and normal to said open end, said magazine including inner and outer cylindrical walls and radial uniformly spaced dividers extending between the walls, said dividers delimiting a series of circumferentially spaced article cells, an access opening in the main door adapted to align with the cells successively as the magazine is rotated, a service latch mounted on the cabinet adjacent the open end thereof adapted to engage the magazine when the door is open to hold a magazine cell in line with the access opening, said service latch having means therein for engagement by the door when the door is closed to release said service latch, a running latch mounted on the door, said running latch engaging the magazine as the door is closed to hold the magazine in aligned cell position when the service latch is released, a drive shaft extending through the door and operable from the exterior thereof, a detachable

drive connection between the shaft and the magazine engageable when the door is closed, coin controlled means for releasably holding the drive shaft from rotation, and means connected to the drive shaft and mounted within the door operative upon release of the holding means and initial movement of the drive shaft to disengage the running latch to permit rotative movement of the magazine and to recondition the running latch to stop movement of the magazine after it has advanced one cell into alignment with the access opening.

4. A dispensing apparatus comprising a cabinet having an open end, a main door for closing said end, a cylindrical magazine rotatably mounted in the cabinet and having its longitudinal axis disposed normal to the closed door, a plurality of radially disposed uniformly spaced dividers in the magazine to partition it into a series of circumferentially spaced cells, an access opening in the door adapted to align successively with said cells as the magazine is rotated, a drive shaft extending through the door and having a detachable ratchet driving connection with the magazine, coin controlled holding means for releasably locking the shaft against rotation in a direction to advance the cells past the access opening, a pair of oppositely directed latch elements mounted on the door and adapted to engage opposite sides of a divider, said latch elements aligning a cell with the access opening, said latch elements being successively disengageable by movement of the divider when the magazine is rotated in one direction, one of said latch elements locking the magazine from rotation in the opposite direction when a divider is positioned between the elements, a holding link for the other latch element, a disengageable connection between the holding link and the drive shaft, means operative as an incident to initial movement of the drive shaft when the shaft locking means are released to release the holding link from said other latch element, means acting sequentially to such movement as the drive shaft continues to rotate in the same direction to break the disengageable connection and to restore the link to holding position for said other latch element, and means reestablishing said disengageable connection between the link and drive shaft when said drive shaft is rotated in a reverse direction.

5. A dispensing apparatus comprising a cabinet having an open end and a door for closing such end, a cylindrical magazine including a plurality of cells rotatably mounted in the magazine, an access opening in the door adapted to align with the cells as the magazine is rotated, and means mounted on the door and engaging the magazine when the door is closed for rotating the magazine and latching the same against rotation, said magazine rotating means including a drive shaft extending through the door for manipulation from the exterior thereof, a driving connection between the inner end of the shaft and the maga-

zine including a lost motion linkage and an overrunning clutch, a plate mounted around the shaft for rotation therewith, said plate being provided with a pin and an offset portion, said latching means including a latch element normally engaging the magazine to restrain the same from rotation and a holding link to prevent disengagement of the latch element, a draw bar connected at one end to the link and detachably engaging the pin on the plate at its opposite end, said pin and draw bar upon initial rotation of the shaft releasing said holding link to permit disengagement of the latch element from the magazine as the shaft absorbs the lost motion in its linkage to the magazine, said offset portion being so positioned as to disengage the draw bar from the pin as the shaft begins to drive the magazine, and means to return the holding link to latch restraining position to prevent overtravel of the magazine.

6. A dispensing apparatus comprising a cabinet, a cylindrical magazine rotatably mounted in the cabinet and having its axis normal to one end thereof, said magazine being formed with inner and outer cylindrical walls and radial dividers partitioning the magazine into a plurality of article cells, an access opening in one end of the cabinet adapted to align with said cells as the magazine is rotated, and means mounted in the cabinet for progressively rotating the magazine through arcs successively presenting said cells to said access opening, said last named means including a latch having elements extending toward the magazine and adapted to grip a divider on opposite sides thereof, each of said latch elements being spring biased into magazine engaging position, one of said latch elements being formed with a positive stop to prevent movement of the magazine in one rotative direction, the other of said elements being provided with a movable stop to prevent movement of the magazine in the opposite rotative direction, a drive shaft extending through the cabinet and coupled to the magazine to effect rotation of the same, means for limiting the arc through which the drive shaft may rotate, and means interconnected between the drive shaft and said movable stop to disengage said stop from the last named latch upon initial rotative movement of the shaft, and to restore said stop to latch engaging position before the drive shaft has reached the limit of its permissible movement.
